DESIGN FOR A MEDICATED VAPORIZER

Theodore A. Andersen, Indianapolis, Ind., assignor to Electric Vapor Corporation, Indianapolis, Ind., a corporation of Indiana

Application November 17, 1937, Serial No. 72,947

Term of patent 3½ years

To all whom it may concern:

Be it known that I, Theodore A. Andersen, a citizen of the United States, residing at Indianapolis, in the county of Marion and State of Indiana, have invented a new, original, and ornamental Design for a Medicated Vaporizer, of which the following is a specification, reference being had to the accompanying drawing, forming part thereof.

Fig. 1 is a side elevational view of a medicated vaporizer embodying my design; and

Fig. 2 is a side elevational view thereof showing the other side of the vaporizer in Fig. 1.

I claim:

The ornamental design for a medicated vaporizer, as shown.

THEODORE A. ANDERSEN.
